(57) **CLAIM**

The ornamental design for a rotary direction indicator, as shown and described.

DESCRIPTION

FIG. 1 is a perspective view of a rotary direction indicator;

FIG. 2 is a top plan view thereof;

FIG. 3 is a front side elevational view thereof;

FIG. 4 is a rear side elevational view thereof;

FIG. 5 is a left side elevational view thereof;

FIG. 6 is a right side elevational view thereof;

FIG. 7 is a bottom plan view thereof;

FIG. 8 is a perspective view of the second embodiment of the rotary direction indicator;

FIG. 9 is a top plan view of the 2nd embodiment shown in FIG. 8;

FIG. 10 is a front side elevational view of the 2nd embodiment shown in FIG. 8;

FIG. 11 is a rear side elevational view of the 2nd embodiment shown in FIG. 8;

FIG. 12 is a left side elevational view of the 2nd embodiment shown in FIG. 8;

FIG. 13 is a right side elevational view of the 2nd embodiment shown in FIG. 8;

FIG. 14 is a bottom plan view of the 2nd embodiment shown in FIG. 8;

FIG. 15 is a top plan view of a third embodiment of the rotary direction indicator;

FIG. 16 is a front side elevational view of a third embodiment shown in FIG. 15, all other side elevational views being identical;

FIG. 17 is a back view of the third embodiment shown in FIG. 15; and,

FIG. 18 is a top plan view of a fourth embodiment of the rotary direction indicator, the side and bottom views being identical to FIGS. 16 and 17, respectively.

No claim is made to the structure in phantom outline.
